(57) **ABSTRACT**

A gaming device includes a display device, an input device, a processor circuit, and a memory. The memory includes machine-readable instructions that, when executed by the processor circuit, cause the processor circuit to receive, by the processor circuit and via an operator processing circuit, identification corresponding to multiple game sets. Each of the game sets may include a subset of games. The processor circuit is caused to determine a recommended game set switch from a first game set to a second game set. The first and second game sets are on an electronic gaming machine (EGM) and the determining is performed using artificial intelligence that uses external data to identify the second game sets. The processor circuit is caused to transmit, to the EGM, an identification of the recommended game set switch.

FIG. 6

GAME SET SWITCHING USING ARTIFICIAL INTELLIGENCE

BACKGROUND

Gaming devices, such as video lottery terminals (VLTs) and/or electronic gaming machines (EGMs) may include multiple games installed thereon. Operators of VLTs and/or EGMs may select less than all of the installed games to be accessible to players. Determining which of the games should be included in a set of game to be presented to the player may be difficult for operators to do effectively.

BRIEF SUMMARY

According to some embodiments, a system includes a processor circuit and a memory having machine-readable instructions. When executed by the processor circuit, the machine-readable instruction cause the processor circuit to receive, by the processor circuit and via an operator processor circuit, an identification of multiple games stored in an electronic gaming machine (EGM), receive, by the processor circuit and via the operator processing circuit, an indication of multiple game sets, each of the game sets including a subset of the games and receive, by the processor circuit and via the input interface, external data corresponding to an event or condition that is external to the EGM. The processor circuit is further caused to determine a recommended game set of the game sets using artificial intelligence and based on the external data and transmit, to the EGM, an indication including a game set switch to the recommended game set, the game set switch including a transition from a first game set to a second game set.

According to some embodiments, a gaming device includes a display device, an input device, a processor circuit, and a memory. The memory includes machine-readable instructions that, when executed by the processor circuit, cause the processor circuit to receive, by the processor circuit and via an operator processing circuit, identification corresponding to multiple game sets. Each of the game sets may include a subset of games.

In some embodiments, the processor circuit is caused to determine a recommended game set switch from a first game set to a second game set. In some embodiments, the first and second game sets are on an electronic gaming machine (EGM) and the determining is performed using artificial intelligence that uses external data to identify the second game sets.

Some embodiments provide that the processor circuit is caused to transmit, to the EGM, an identification of the recommended game set switch.

According to some embodiments, a method includes operations including receiving, by a processor circuit, an identification of multiple games stored in an electronic gaming machine (EGM) and receiving, by the processor circuit, an identification of multiple game sets. Each of the game sets may be a subset of the multiple of games. Operations may include receiving, by the processor circuit, external data corresponding to a factor that is external to the EGM and determining a recommended game set using artificial intelligence and based on the external data. Operations may include causing the EGM perform a game set switch to display the recommended game set.

BRIEF DESCRIPTION OF SEVERAL VIEWS OF THE DRAWINGS

FIG. 1 is a schematic block diagram illustrating a network configuration for a plurality of gaming devices according to some embodiments.

FIG. 2A is a perspective view of a gaming device that can be configured according to some embodiments.

FIG. 2B is a schematic block diagram illustrating an electronic configuration for a gaming device according to some embodiments.

FIG. 2C is a schematic block diagram that illustrates various functional modules of a gaming device according to some embodiments.

FIG. 2D is perspective view of a gaming device that can be configured according to some embodiments.

FIG. 2E is a perspective view of a gaming device according to further embodiments.

FIG. 3 is a schematic diagram of a system with a game set recommender for operators according to some embodiments.

FIG. 4 is a flowchart illustrating operations of systems/methods with a game set recommender for providing artificial intelligence game switching according to some embodiments.

FIG. 5 is a flowchart illustrating operations of systems/methods with a game set recommender for providing artificial intelligence game switching according to some embodiments.

FIG. 6 is a flowchart illustrating operations of systems/methods with a game set recommender for providing artificial intelligence game switching according to some embodiments.

DETAILED DESCRIPTION

Embodiments described herein are directed to provide smart switching to support switching between game sets based on Artificial Intelligence (AI). In some embodiments, external and/or environmental input to AI may be used to determine a game set, which may include a group of games and/or a game collection and may provide an operation for swapping the games being offered to a player via the gaming device. As provided herein, a gaming device may include a VLT and/or an EGM. Further, any operation described herein based on using one of a VLT or EGM may be performed and/or used with the other one of the VLT or EGM.

In some embodiments, a gaming device may take a picture of a player when they commence playing and send the picture to the operator of the gaming device and a host system that includes AI. The host system may decide what type of game to offer the player based on data provided to the gaming device, the host system and/or the operator. For example, a gaming device may utilize the data corresponding to the picture to determine that the player may prefer sports team, among others. Similarly, the picture may be sent to the host system, which may use AI to determine which games to offer the player. For example, in response to receiving and analyzing the picture, the AI may cause a game to be switched out and replaced with a different game.

Some embodiments provide that a gaming device may include 50 or more games stored thereon. In some embodiments, the 50 or more games may be grouped into game sets of five to ten games. In some embodiments, artificial intelligence (AI) that is a component of the host system may be used to determine which game sets should be presented by the gaming device to the player. Some embodiments provide that a game and/or game set is switched out to be replaced by a different game and/or game set.

In some embodiments, AI may be included in the gaming device to determine games and/or game sets that may be interesting to the player. In some embodiments, it may be

determined that a player may have interest in a particular theme or activity. The AI may use this information coupled with data corresponding to external events to recommend a game set switch from a first game set to a second game set.

In some embodiments, the game set switches based on AI may be based on external inputs and/or events. External inputs or events may be based on weather, financial markets, seasons, gender, clothes color, environmental color and/or lighting, nighttime or daytime, day of the week, and/or weekend or weekday, among others.

In some embodiments, the gaming device may request that the host system identify a different game. Such requesting may be based on an assumption that the current player is likely to be on the gaming device for enough time to download requested game and/or game set.

Embodiments include determining feedback regarding the performance and/or effectiveness of a game set switch. Such feedback may be used to determine if the switch was an advantageous change or not.

As provided herein, a game set switch may describe a transition from a first game set to a second game set.

In some embodiments, metrics corresponding to game set may include the order that the games within the game set are presented. For example, the AI may determine that a given player will be more receptive to a particular game in the game set. In such cases, that preferred game may be presented first relative to other games in the game set. In some embodiments, a new game and/or a game that the player has not seen may be presented first to allow the player to be exposed to a new game before seeing the other games in the set.

In some embodiments, a game set that the AI determines would be attractive to a player may be on a different gaming device that is near the gaming device that the player is using. In such circumstances, the gaming device that the player is using may provide a message to the player that invites the player to move to the machine having the game set that the AI determines would be attractive to that player. In some embodiments, the gaming device may provide an incentive for the player to move to another machine by offering free spins and/or bonus awards.

Some embodiments provide that game performance, game set switches and feedback corresponding to game set switches may be provided to the operator and/or an operator processor circuit.

In some embodiments, a player profile may be received by the AI and may include multiple inputs for the AI to use in determining future game set switches and/or feedback regarding to previous game set switches.

In some embodiments, after a player has left a gaming device, a recommendation for another gaming device may be sent to the player by sending a notification to a player's mobile device.

In some embodiments, a player's preferences may change depending on a different venue and/or venue type. In this regard, venue and/or venue type may be used by the AI to determine a game set switch. In this regarding the player's interests may vary depending on venue.

In some embodiments, in response to a player leaving a venue, the player may be offered the identity of a game at another venue by sending a message to the player's mobile device offering to provide a player's preferred game at the other venue. Some embodiments provide that start downloading the game and/or game set to a gaming device at the destination venue before the player arrives.

Referring now to FIG. 1, a gaming system 10 including a plurality of gaming devices 100 is illustrated. As discussed

above, the gaming devices 100 may be one type of a variety of different types of gaming devices, such as electronic gaming machines (EGMs), video lottery terminals, mobile gaming devices, or other devices, for example. The gaming system 10 may be located, for example, on the premises of a gaming establishment, such as a casino. The gaming devices 100, which are typically situated on a casino floor, may be in communication with each other and/or at least one central controller 40 through a data communication network 50 that may include a remote communication link. The data communication network 50 may be a private data communication network that is operated, for example, by the gaming facility that operates the gaming devices 100. Communications over the data communication network 50 may be encrypted for security. The central controller 40 may be any suitable server or computing device which includes at least one processing circuit and at least one memory or storage device. Each gaming device 100 may include a processing circuit that transmits and receives events, messages, commands or any other suitable data or signal between the gaming device 100 and the central controller 40. The gaming device processing circuit is operable to execute such communicated events, messages or commands in conjunction with the operation of the gaming device 100. Moreover, the processing circuit of the central controller 40 is configured to transmit and receive events, messages, commands or any other suitable data or signal between the central controller 40 and each of the individual gaming devices 100. In some embodiments, one or more of the functions of the central controller 40 may be performed by one or more gaming device processing circuits. Moreover, in some embodiments, one or more of the functions of one or more gaming device processing circuits as disclosed herein may be performed by the central controller 40.

A wireless access point 60 provides wireless access to the data communication network 50. The wireless access point 60 may be connected to the data communication network 50 as illustrated in FIG. 1, and/or may be connected directly to the central controller 40 or another server connected to the data communication network 50.

A player tracking server 45 may also be connected through the data communication network 50. The player tracking server 45 may manage a player tracking account that tracks the player's gameplay and spending and/or other player preferences and customizations, manages loyalty awards for the player, manages funds deposited or advanced on behalf of the player, and other functions. Player information managed by the player tracking server 45 may be stored in a player information database 47.

As further illustrated in FIG. 1, the gaming system 10 may include a ticket server 90 that is configured to print and/or dispense wagering tickets. The ticket server 90 may be in communication with the central controller 40 through the data communication network 50. Each ticket server 90 may include a processing circuit that transmits and receives events, messages, commands or any other suitable data or signal between the ticket server 90 and the central controller 40. The ticket server 90 processing circuit may be operable to execute such communicated events, messages or commands in conjunction with the operation of the ticket server 90. Moreover, in some embodiments, one or more of the functions of one or more ticket server 90 processing circuits as disclosed herein may be performed by the central controller 40.

As further illustrated in FIG. 1, an operator server may provide management, control and operational control of the gaming devices 100. In some embodiments, the operator

server may access the gaming devices using the network, however, the operator server 75 may be directly connected to one or more of the gaming devices 100.

In some embodiments, the operator server 75 may communicate with a host system 70 that is configured to provide recommendations to the operator server 75 regarding games in game sets that are available to the player at the gaming devices 100. In some embodiments, the host system 70 receives data from the operator server 75 that indicates which game or games are to be selected for the gaming devices 100. In some embodiments, the host system 70 may receive game set information from the gaming devices 100.

The gaming devices 100 communicate with one or more elements of the gaming system 10 to coordinate providing wagering games and other functionality. For example, in some embodiments, the gaming device 100 may communicate directly with the ticket server 90 over a wireless interface 62, which may be a WiFi link, a Bluetooth link, a near field communications (NFC) link, etc. In other embodiments, the gaming device 100 may communicate with the data communication network 50 (and devices connected thereto, including other gaming devices 100) over a wireless interface 64 with the wireless access point 60. The wireless interface 64 may include a WiFi link, a Bluetooth link, an NFC link, etc. In still further embodiments, the gaming devices 100 may communicate simultaneously with both the ticket server 90 over the wireless interface 66 and the wireless access point 60 over the wireless interface 64. Some embodiments provide that gaming devices 100 may communicate with other gaming devices over a wireless interface 64. In these embodiments, wireless interface 62, wireless interface 64 and wireless interface 66 may use different communication protocols and/or different communication resources, such as different frequencies, time slots, spreading codes, etc.

Embodiments herein may include different types of gaming devices. One example of a gaming device includes a gaming device 100 that can use gesture and/or touch-based inputs according to various embodiments is illustrated in FIGS. 2A, 2B, and 2C in which FIG. 2A is a perspective view of a gaming device 100 illustrating various physical features of the device, FIG. 2B is a functional block diagram that schematically illustrates an electronic relationship of various elements of the gaming device 100, and FIG. 2C illustrates various functional modules that can be stored in a memory device of the gaming device 100. The embodiments shown in FIGS. 2A to 2C are provided as examples for illustrative purposes only. It will be appreciated that gaming devices may come in many different shapes, sizes, layouts, form factors, and configurations, and with varying numbers and types of input and output devices, and that embodiments are not limited to the particular gaming device structures described herein.

Gaming devices 100 typically include a number of standard features, many of which are illustrated in FIGS. 2A and 2B. For example, referring to FIG. 2A, a gaming device 100 (which is an EGM 160 in this embodiment) may include a support structure, housing 105 (e.g., cabinet) which provides support for a plurality of displays, inputs, outputs, controls and other features that enable a player to interact with the gaming device 100.

The gaming device 100 illustrated in FIG. 2A includes a number of display devices, including a primary display device 116 located in a central portion of the housing 105 and a secondary display device 118 located in an upper portion of the housing 105. A plurality of game components 155 are displayed on a display screen 117 of the primary

display device 116. It will be appreciated that one or more of the display devices 116, 118 may be omitted, or that the display devices 116, 118 may be combined into a single display device. The gaming device 100 may further include 5 a player tracking display 142, a credit display 120, and a bet display 122. The credit display 120 displays a player's current number of credits, cash, account balance or the equivalent. The bet display 122 displays a player's amount wagered. Locations of these displays are merely illustrative 10 as any of these displays may be located anywhere on the gaming device 100.

The player tracking display 142 may be used to display a service window that allows the player to interact with, for example, their player loyalty account to obtain features, 15 bonuses, comps, etc. In other embodiments, additional display screens may be provided beyond those illustrated in FIG. 2A. In some embodiments, one or more of the player tracking display 142, the credit display 120 and the bet display 122 may be displayed in one or more portions of one 20 or more other displays that display other game related visual content. For example, one or more of the player tracking display 142, the credit display 120 and the bet display 122 may be displayed in a picture in a picture on one or more displays.

25 The gaming device 100 may further include a number of input devices 130 that allow a player to provide various inputs to the gaming device 100, either before, during or after a game has been played. The gaming device may further include a game play initiation button 132 and a 30 cashout button 134. The cashout button 134 is utilized to receive a cash payment or any other suitable form of payment corresponding to a quantity of remaining credits of a credit display.

In some embodiments, one or more input devices of the 35 gaming device 100 are one or more game play activation devices that are each used to initiate a play of a game on the gaming device 100 or a sequence of events associated with the gaming device 100 following appropriate funding of the gaming device 100. The example gaming device 100 illustrated in FIGS. 2A and 2B includes a game play activation device in the form of a game play initiation button 132. It 40 should be appreciated that, in other embodiments, the gaming device 100 begins game play automatically upon appropriate funding rather than upon utilization of the game play activation device.

In some embodiments, one or more input device 130 of the 45 gaming device 100 may include wagering or betting functionality. For example, a maximum wagering or betting function may be provided that, when utilized, causes a maximum wager to be placed. Another such wagering or betting function is a repeat the bet device that, when utilized, causes the previously-placed wager to be placed. A further such wagering or betting function is a bet one function. A bet is placed upon utilization of the bet one function. The bet is increased by one credit each time the bet one device is utilized. Upon the utilization of the bet one function, a quantity of credits shown in a credit display (as described below) decreases by one, and a number of credits shown in a bet display (as described below) increases by one.

50 In some embodiments, as shown in FIG. 2B, the input device(s) 130 may include and/or interact with additional components, such as gesture sensors 156 for gesture input devices, and/or a touch-sensitive display that includes a digitizer 152 and a touchscreen controller 154 for touch input devices, as disclosed herein. The player may interact 55 with the gaming device 100 by touching virtual buttons on one or more of the display devices 116, 118, 140. Accord-

ingly, any of the above-described input devices, such as the input device 130, the game play initiation button 132 and/or the cashout button 134 may be provided as virtual buttons or regions on one or more of the display devices 116, 118, 140.

Referring briefly to FIG. 2B, operation of the primary display device 116, the secondary display device 118 and the player tracking display 142 may be controlled by a video controller 30 that receives video data from a processing circuit 12 or directly from a memory device 14 and displays the video data on the display screen. The credit display 120 and the bet display 122 are typically implemented as simple liquid crystal display (LCD) or light emitting diode (LED) displays that display a number of credits available for wagering and a number of credits being wagered on a particular game. Accordingly, the credit display 120 and the bet display 122 may be driven directly by the processing circuit 12. In some embodiments however, the credit display 120 and/or the bet display 122 may be driven by the video controller 30.

Referring again to FIG. 2A, the display devices 116, 118, 140 may include, without limitation: a cathode ray tube, a plasma display, an LCD, a display based on LEDs, a display based on a plurality of organic light-emitting diodes (OLEDs), a display based on polymer light-emitting diodes (PLEDs), a display based on a plurality of surface-conduction electron-emitters (SEDs), a display including a projected and/or reflected image, or any other suitable electronic device or display mechanism. In certain embodiments, as described above, the display devices 116, 118, 140 may include a touch-screen with an associated touchscreen controller 154 and digitizer 152. The display devices 116, 118, 140 may be of any suitable size, shape, and/or configuration. The display devices 116, 118, 140 may include flat or curved display surfaces.

The display devices 116, 118, 140 and video controller 30 of the gaming device 100 are generally configured to display one or more game and/or non-game images, symbols, and indicia. In certain embodiments, the display devices 116, 118, 140 of the gaming device 100 are configured to display any suitable visual representation or exhibition of the movement of objects; dynamic lighting; video images; images of people, characters, places, things, and faces of cards; and the like. In certain embodiments, the display devices 116, 118, 140 of the gaming device 100 are configured to display one or more virtual reels, one or more virtual wheels, and/or one or more virtual dice. In other embodiments, certain of the displayed images, symbols, and indicia are in mechanical form. That is, in these embodiments, the display device 116, 118, 140 includes any electromechanical device, such as one or more rotatable wheels, one or more reels, and/or one or more dice, configured to display at least one or a plurality of game or other suitable images, symbols, or indicia.

The gaming device 100 also includes various features that enable a player to deposit credits in the gaming device 100 and withdraw credits from the gaming device 100, such as in the form of a payout of winnings, credits, etc. For example, the gaming device 100 may include a bill/ticket dispenser 136, a bill/ticket acceptor 128, and a coin acceptor 126 that allows the player to deposit coins into the gaming device 100.

As illustrated in FIG. 2A, the gaming device 100 may also include a currency dispenser 137 that may include a note dispenser configured to dispense paper currency and/or a coin generator configured to dispense coins or tokens in a coin payout tray.

The gaming device 100 may further include one or more speakers 150 controlled by one or more sound cards 28

(FIG. 2B). The gaming device 100 illustrated in FIG. 2A includes a pair of speakers 150. In other embodiments, additional speakers, such as surround sound speakers, may be provided within or on the housing 105. Moreover, the gaming device 100 may include built-in seating with integrated headrest speakers.

In various embodiments, the gaming device 100 may generate dynamic sounds coupled with attractive multimedia images displayed on one or more of the display devices 116, 118, 140 to provide an audio-visual representation or to otherwise display full-motion video with sound to attract players to the gaming device 100 and/or to engage the player during gameplay. In certain embodiments, the gaming device 100 may display a sequence of audio and/or visual attraction messages during idle periods to attract potential players to the gaming device 100. The videos may be customized to provide any appropriate information.

The gaming device 100 may further include a card reader 138 that is configured to read magnetic stripe cards, such as player loyalty/tracking cards, chip cards, and the like. In some embodiments, a player may insert an identification card into a card reader of the gaming device. In some embodiments, the identification card is a smart card having a programmed microchip or a magnetic strip coded with a player's identification, credit totals (or related data) and other relevant information. In other embodiments, a player may carry a portable device, such as a cell phone, a radio frequency identification tag or any other suitable wireless device, which communicates a player's identification, credit totals (or related data) and other relevant information to the gaming device. In some embodiments, money may be transferred to a gaming device through electronic funds transfer. When a player funds the gaming device, the processing circuit determines the amount of funds entered and displays the corresponding amount on the credit or other suitable display as described above.

In some embodiments, the gaming device 100 may include an electronic payout device or module configured to fund an electronically recordable identification card or smart card or a bank or other account via an electronic funds transfer to or from the gaming device 100.

FIG. 2B is a block diagram that illustrates logical and functional relationships between various components of a gaming device 100. It should also be understood that components described in FIG. 2B may also be used in other computing devices, as desired, such as mobile computing devices for example. As shown in FIG. 2B, the gaming device 100 may include a processing circuit 12 that controls operations of the gaming device 100. Although illustrated as a single processing circuit, multiple special purpose and/or general purpose processors and/or processor cores may be provided in the gaming device 100. For example, the gaming device 100 may include one or more of a video processor, a signal processor, a sound processor and/or a communication controller that performs one or more control functions within the gaming device 100. The processing circuit 12 may be variously referred to as a "controller," "microcontroller," "microprocessor" or simply a "computer." The processor may further include one or more application-specific integrated circuits (ASICs).

Various components of the gaming device 100 are illustrated in FIG. 2B as being connected to the processing circuit 12. It will be appreciated that the components may be connected to the processing circuit 12 through a system bus 151, a communication bus and controller, such as a universal serial bus (USB) controller and USB bus, a network interface, or any other suitable type of connection.

The gaming device 100 further includes a memory device 14 that stores one or more functional modules 20. Various functional modules 20 of the gaming device 100 will be described in more detail below in connection with FIG. 2D.

The memory device 14 may store program code and instructions, executable by the processing circuit 12, to control the gaming device 100. The memory device 14 may also store other data such as image data, event data, player input data, random or pseudo-random number generators, pay-table data or information and applicable game rules that relate to the play of the gaming device. The memory device 14 may include random access memory (RAM), which can include non-volatile RAM (NVRAM), magnetic RAM (ARAM), ferroelectric RAM (FeRAM) and other forms as commonly understood in the gaming industry. In some embodiments, the memory device 14 may include read only memory (ROM). In some embodiments, the memory device 14 may include flash memory and/or EEPROM (electrically erasable programmable read only memory). Any other suitable magnetic, optical and/or semiconductor memory may operate in conjunction with the gaming device disclosed herein.

The gaming device 100 may further include a data storage 22, such as a hard disk drive or flash memory. The data storage 22 may store program data, player data, audit trail data or any other type of data. The data storage 22 may include a detachable or removable memory device, including, but not limited to, a suitable cartridge, disk, CD ROM, Digital Video Disc ("DVD") or USB memory device.

The gaming device 100 may include a communication adapter 26 that enables the gaming device 100 to communicate with remote devices over a wired and/or wireless communication network, such as a local area network (LAN), wide area network (WAN), cellular communication network, or other data communication network. The communication adapter 26 may further include circuitry for supporting short range wireless communication protocols, such as Bluetooth and/or NFC that enable the gaming device 100 to communicate, for example, with a mobile communication device operated by a player.

The gaming device 100 may include one or more internal or external communication ports that enable the processing circuit 12 to communicate with and to operate with internal or external peripheral devices, such as eye tracking devices, position tracking devices, cameras, accelerometers, arcade sticks, bar code readers, bill validators, biometric input devices, bonus devices, button panels, card readers, coin dispensers, coin hoppers, display screens or other displays or video sources, expansion buses, information panels, keypads, lights, mass storage devices, microphones, motion sensors, motors, printers, reels, Small Computer System Interface ("SCSI") ports, solenoids, speakers, thumb drives, ticket readers, touch screens, trackballs, touchpads, wheels, and wireless communication devices. In some embodiments, internal or external peripheral devices may communicate with the processing circuit through a USB hub (not shown) connected to the processing circuit 12.

In some embodiments, the gaming device 100 may include a sensor, such as a camera 127, in communication with the processing circuit 12 (and possibly controlled by the processing circuit 12) that is selectively positioned to acquire an image of a player actively using the gaming device 100 and/or the surrounding area of the gaming device 100. In one embodiment, the camera 127 may be configured to selectively acquire still or moving (e.g., video) images and may be configured to acquire the images in either an analog, digital or other suitable format. The display devices

116, 118, 140 may be configured to display the image acquired by the camera 127 as well as display the visible manifestation of the game in split screen or picture-in-picture fashion. For example, the camera 127 may acquire an image of the player and the processing circuit 12 may incorporate that image into the primary and/or secondary game as a game image, symbol or indicia.

Various functional modules of that may be stored in a memory device 14 of a gaming device 100 are illustrated in FIG. 2C. Referring to FIG. 2C, the gaming device 100 may include in the memory device 14 a game module 20A that includes program instructions and/or data for operating a hybrid wagering game as described herein. The gaming device 100 may further include a player tracking module 20B, an electronic funds transfer module 20C, an input device interface 20D, an audit/reporting module 20E, a communication module 20F, an operating system kernel 20G and a random number generator 20H. The player tracking module 20B keeps track of the play of a player. The electronic funds transfer module 20C communicates with a back end server or financial institution to transfer funds to and from an account associated with the player. The input device interface 20D interacts with input devices, such as the input device 130, as described in more detail below. The communication module 20F enables the gaming device 100 to communicate with remote servers and other gaming devices using various secure communication interfaces. The operating system kernel 20G controls the overall operation of the gaming device 100, including the loading and operation of other modules. The random number generator 20H generates random or pseudorandom numbers for use in the operation of the hybrid games described herein.

In some embodiments, a gaming device 100 includes a personal device, such as a desktop computer, a laptop computer, a mobile device, a tablet computer or computing device, a personal digital assistant (PDA), or other portable computing devices. In some embodiments, the gaming device 100 may be operable over a wireless network, such as part of a wireless gaming system. In such embodiments, the gaming machine may be a hand-held device, a mobile device or any other suitable wireless device that enables a player to play any suitable game at a variety of different locations. It should be appreciated that a gaming device or gaming machine as disclosed herein may be a device that has obtained approval from a regulatory gaming commission or a device that has not obtained approval from a regulatory gaming commission.

For example, referring to FIG. 2D, a gaming device 100 (which is a mobile gaming device 170 in this embodiment) may be implemented as a handheld device including a compact housing 105 on which is mounted a touchscreen display device 116 including a digitizer 152. As described in greater detail below, one or more input devices 130 may be included for providing functionality of for embodiments described herein. A camera 127 may be provided in a front face of the housing 105. The housing 105 may include one or more speakers 150. In the gaming device 100, various input buttons described above, such as the cashout button, gameplay activation button, etc., may be implemented as soft buttons on the touchscreen display device 116 and/or input device 130. In this embodiment, the input device 130 is integrated into the touchscreen display device 116, but it should be understood that the input device may also, or alternatively, be separate from the display device 116. Moreover, the gaming device 100 may omit certain features, such as a bill acceptor, a ticket generator, a coin acceptor or dispenser, a card reader, secondary displays, a bet display, a

credit display, etc. Credits can be deposited in or transferred from the gaming device 100 electronically.

FIG. 2E illustrates a standalone gaming device 100 (which is an EGM 160 in this embodiment) having a different form factor from the EGM 160 illustrated in FIG. 2A. In particular, the gaming device 100 is characterized by having a large, high aspect ratio, curved primary display device 116 provided in the housing 105, with no secondary display device. The primary display device 116 may include a digitizer 152 to allow touchscreen interaction with the primary display device 116. The gaming device 100 may further include a player tracking display 142, an input device 130, a bill/ticket acceptor 128, a card reader 138, and a bill/ticket dispenser 136. The gaming device 100 may further include one or more cameras 127 to enable facial recognition and/or motion tracking.

Although illustrated as certain gaming devices, such as electronic gaming machines (EGMs) and mobile gaming devices, functions and/or operations as described herein may also include wagering stations that may include electronic game tables, conventional game tables including those involving cards, dice and/or roulette, and/or other wagering stations such as sports book stations, video poker games, skill-based games, virtual casino-style table games, or other casino or non-casino style games. Further, gaming devices according to embodiments herein may be implemented using other computing devices and mobile devices, such as smart phones, tablets, and/or personal computers, among others.

Reference is now made to FIG. 3, which is a schematic block diagram illustrating a system including a game set recommender for an operator according to some embodiments. As illustrated, the system includes an operator 320 of a gaming device 100. In some embodiments, the operator 320 may be one or more servers and/or one or more graphical interfaces. For example, the operator 320 may log into a graphical user interface provided by a host system 310, which is configured to use artificial intelligence 311 to provide game set switching for game sets for use in the gaming device 100. In some embodiments, the game set recommender receives data for making a recommendation from the operator, from the gaming device 100 and/or from input data that is received from sources outside the system. Although illustrated as only having a single gaming device 100, embodiments include systems having many gaming devices that may be managed by the operator 320.

In some embodiments, the gaming device 100 may optionally include artificial intelligence 312 that may be configured to provide analytical data corresponding to inputs received at the gaming device 100.

Reference is now made to FIG. 4, which is a flowchart illustrating operations of systems/methods with a host system for providing artificial intelligence game switching according to some embodiments. Systems herein may include an input interface, a processor circuit, and a memory including machine-readable instructions that, when executed by the processor circuit, cause the processor circuit to receive (Block 402), by the processor circuit and via an operator processor circuit, an identification of a plurality of games stored in an electronic gaming machine (EGM). The processor circuit may be caused to receive (Block 404), by the processor circuit and via the operator processing circuit, an indication of multiple game sets. In some embodiments, each of the game sets includes a subset of the games. The processor circuit may be caused to receive (Block 406), by

the processor circuit and via the input interface, external data corresponding to an event or condition that is external to the EGM.

Some embodiments provide that the processor circuit is caused to determine (Block 408) a recommended game set of the game sets using artificial intelligence and based on the external data. The processor circuit may be caused to transmit (Block 410), to the EGM, an indication including a game set switch to the recommended game set. In some embodiments, the game set switch includes a transition from a first game set to a second game set.

Some embodiments provide that the external data corresponds to a player that is playing the EGM. In some embodiments, data corresponding to the player includes image data generated by a camera at the EGM.

In some embodiments, the external data includes a history-based prediction of a type of game that the player has played and of an amount of time that the player has played the type of game. Some embodiments provide that the recommended game set provided by the artificial intelligence uses the amount of time that the player is playing a given game to determine if a game that is not one of the games may be downloaded before the player leaves the given game.

In some embodiments, the processor circuit is further configured to receive (Block 412), from the operator processor circuit, a request for the recommended game set. Some embodiments provide that determining the recommended game set is performed responsive to receiving the request.

Some embodiments provide that, responsive to an active game set being switched to the recommended game set, the processor circuit is further configured to receive (Block 414) feedback data that corresponds to the recommended game set after a current game set is switched.

Some embodiments provide that the processor circuit is further configured to receive game set metrics that include quantitative data corresponding to performance of ones of the game sets. The processor circuit may determine (Block 416) an order of games within one of game sets. The order of games may define the order that the games are presented to a player.

The processor circuit is further configured to cause (Block 418) a message to be sent to a player of a first EGM. The message may include an invitation change to a second EGM to access one of the game sets that is not on the first EGM. In some embodiments, the message further includes an incentive to the player to switch to the second EGM. Incentives may include free spins and/or bonus points, bonus spins and/or bonus value to be spent by the player. The message may include directions to the second EGM from the first EGM.

Some embodiments provide that the processor circuit is further configured to cause (Block 420) a message to be sent to a player that is not in a first venue. In some embodiments, the message includes an invitation go to the first venue to access one of the game sets that is not at a player location and directions for the player to go to the first venue. In some embodiments, the processor circuit is caused to receive (Block 422) a confirmation that the player is going to the first venue. One of game sets may be caused (Block 424) to be switched to access the one of the game sets while the player is in route to the first venue.

In some embodiments, the processor circuit is further configured to cause (Block 426) a message to be sent to a player. The message may include a request from the player to an operator to get one of the game sets.

In some embodiments, the artificial intelligence includes a first artificial intelligence that is provided by the processor circuit. The processor circuit may be further configured to receive a request from the EGM that includes a second artificial intelligence that is provided by the EGM. In some embodiments, the second artificial intelligence is configured to determine an EGM specific recommended set based on data that is specific to the EGM.

Some embodiments provide that the data that is specific to the EGM comprises EGM environmental data.

Reference is now made to FIG. 5, which is a flowchart illustrating operations of systems/methods with a host system for providing artificial intelligence game switching according to some embodiments. Some embodiments include a host device that includes a processor circuit and a memory including machine-readable instructions that, when executed by the processor circuit, cause the processor circuit to receive (Block 502), by the processor circuit and via an operator processing circuit, identification corresponding to multiple game sets. Each of the game sets may include a subset of games.

In some embodiments, the processor circuit is caused to determine (Block 504) a recommended game set switch from a first game set to a second game set. In some embodiments, the first and second game sets are on an electronic gaming machine (EGM) and the determining is performed using artificial intelligence that uses external data to identify the second game sets.

Some embodiments provide that the processor circuit is caused to transmit (Block 506), to the EGM, an identification of the recommended game set switch.

Reference is now made to FIG. 6, which is a flowchart illustrating operations of systems/methods with a host system for providing artificial intelligence game switching according to some embodiments. According to some embodiments, methods herein may perform operations including receiving (Block 602), by a processor circuit, an identification of multiple games stored in an electronic gaming machine (EGM) and receiving (Block 604), by the processor circuit, an identification of multiple game sets. Each of the game sets may be a subset of the multiple of games. Operations may include receiving (Block 606), by the processor circuit, external data corresponding to a factor that is external to the EGM and determining (Block 608) a recommended game set using artificial intelligence and based on the external data. Operations may include causing (Block 610) the EGM perform a game set switch to display the recommended game set.

Embodiments described herein may be implemented in various configurations for gaming devices 100, including but not limited to: (1) a dedicated gaming device, wherein the computerized instructions for controlling any games (which are provided by the gaming device) are provided with the gaming device prior to delivery to a gaming establishment; and (2) a changeable gaming device, where the computerized instructions for controlling any games (which are provided by the gaming device) are downloadable to the gaming device through a data network when the gaming device is in a gaming establishment. In some embodiments, the computerized instructions for controlling any games are executed by at least one central server, central controller or remote host. In such a “thin client” embodiment, the central server remotely controls any games (or other suitable interfaces) and the gaming device is utilized to display such games (or suitable interfaces) and receive one or more inputs or commands from a player. In another embodiment, the computerized instructions for controlling

any games are communicated from the central server, central controller or remote host to a gaming device local processor and memory devices. In such a “thick client” embodiment, the gaming device local processor executes the communicated computerized instructions to control any games (or other suitable interfaces) provided to a player.

In some embodiments, a gaming device may be operated by a mobile device, such as a mobile telephone, tablet other mobile computing device. For example, a mobile device 10 may be communicatively coupled to a gaming device and may include a user interface that receives user inputs that are received to control the gaming device. The user inputs may be received by the gaming device via the mobile device.

In some embodiments, one or more gaming devices in a 15 gaming system may be thin client gaming devices and one or more gaming devices in the gaming system may be thick client gaming devices. In another embodiment, certain functions of the gaming device are implemented in a thin client environment and certain other functions of the gaming 20 device are implemented in a thick client environment. In one such embodiment, computerized instructions for controlling any primary games are communicated from the central server to the gaming device in a thick client configuration and computerized instructions for controlling any secondary games or bonus functions are executed by a central server in a thin client configuration.

The present disclosure contemplates a variety of different 25 gaming systems each having one or more of a plurality of different features, attributes, or characteristics. It should be 30 appreciated that a “gaming system” as used herein refers to various configurations of: (a) one or more central servers, central controllers, or remote hosts; (b) one or more gaming devices; and/or (c) one or more personal gaming devices, such as desktop computers, laptop computers, tablet computers or computing devices, PDAs, mobile telephones such as smart phones, and other mobile computing devices.

In certain such embodiments, computerized instructions 35 for controlling any games (such as any primary or base games and/or any secondary or bonus games) displayed by the 40 gaming device are executed by the central server, central controller, or remote host. In such “thin client” embodiments, the central server, central controller, or remote host remotely controls any games (or other suitable interfaces) displayed by the gaming device, and the gaming device is utilized to display such games (or suitable interfaces) and to receive one or more inputs or commands. In other such 45 embodiments, computerized instructions for controlling any games displayed by the gaming device are communicated from the central server, central controller, or remote host to the gaming device and are stored in at least one memory device of the gaming device. In such “thick client” embodiments, the at least one processor of the gaming device executes the computerized instructions to control any games (or other suitable interfaces) displayed by the gaming 50 device.

In some embodiments in which the gaming system includes: (a) a gaming device configured to communicate with a central server, central controller, or remote host through a data network; and/or (b) a plurality of gaming 55 devices configured to communicate with one another through a data network, the data network is an internet or an intranet. In certain such embodiments, an internet browser of the gaming device is usable to access an internet game page from any location where an internet connection is available. In one such embodiment, after the internet game page is accessed, the central server, central controller, or remote host identifies a player prior to enabling that player to place

15

any wagers on any plays of any wagering games. In one example, the central server, central controller, or remote host identifies the player by requiring a player account of the player to be logged into via an input of a unique username and password combination assigned to the player. It should be appreciated, however, that the central server, central controller, or remote host may identify the player in any other suitable manner, such as by validating a player tracking identification number associated with the player; by reading a player tracking card or other smart card inserted into a card reader (as described below); by validating a unique player identification number associated with the player by the central server, central controller, or remote host; or by identifying the gaming device, such as by identifying the MAC address or the IP address of the internet facilitator. In various embodiments, once the central server, central controller, or remote host identifies the player, the central server, central controller, or remote host enables placement of one or more wagers on one or more plays of one or more primary or base games and/or one or more secondary or bonus games, and displays those plays via the internet browser of the gaming device.

It should be appreciated that the central server, central controller, or remote host and the gaming device are configured to connect to the data network or remote communications link in any suitable manner. In various embodiments, such a connection is accomplished via: a conventional phone line or other data transmission line, a digital subscriber line (DSL), a T-1 line, a coaxial cable, a fiber optic cable, a wireless or wired routing device, a mobile communications network connection (such as a cellular network or mobile internet network), or any other suitable medium. It should be appreciated that the expansion in the quantity of computing devices and the quantity and speed of internet connections in recent years increases opportunities for players to use a variety of gaming devices to play games from an ever-increasing quantity of remote sites. It should also be appreciated that the enhanced bandwidth of digital wireless communications may render such technology suitable for some or all communications, particularly if such communications are encrypted. Higher data transmission speeds may be useful for enhancing the sophistication and response of the display and interaction with players.

In the above-description of various embodiments, various aspects may be illustrated and described herein in any of a number of patentable classes or contexts including any new and useful process, machine, manufacture, or composition of matter, or any new and useful improvement thereof. Accordingly, various embodiments described herein may be implemented entirely by hardware, entirely by software (including firmware, resident software, micro-code, etc.) or by combining software and hardware implementation that may all generally be referred to herein as a "circuit," "module," "component," or "system." Furthermore, various embodiments described herein may take the form of a computer program product including one or more computer readable media having computer readable program code embodied thereon.

Any combination of one or more computer readable media may be used. The computer readable media may be a computer readable signal medium or a computer readable storage medium. A computer readable storage medium may be, for example, but not limited to, an electronic, magnetic, optical, electromagnetic, or semiconductor system, apparatus, or device, or any suitable combination of the foregoing. More specific examples (a non-exhaustive list) of the computer readable storage medium would include the following:

16

a portable computer diskette, a hard disk, a random access memory (RAM), a read-only memory (ROM), an erasable programmable read-only memory (EPROM or Flash memory), an appropriate optical fiber with a repeater, a portable compact disc read-only memory (CD-ROM), an optical storage device, a magnetic storage device, or any suitable combination of the foregoing. In the context of this document, a computer readable storage medium may be any medium that can contain, or store a program for use by or in connection with an instruction execution system, apparatus, or device.

A computer readable signal medium may include a propagated data signal with computer readable program code embodied therein, for example, in baseband or as part of a carrier wave. Such a propagated signal may take any of a variety of forms, including, but not limited to, electromagnetic, optical, or any suitable combination thereof. A computer readable signal medium may be any computer readable medium that is not a computer readable storage medium and that can communicate, propagate, or transport a program for use by or in connection with an instruction execution system, apparatus, or device. Program code embodied on a computer readable signal medium may be transmitted using any appropriate medium, including but not limited to wireless, wireline, optical fiber cable, radio frequency ("RF"), etc., or any suitable combination of the foregoing.

Computer program code for carrying out operations for aspects of the present disclosure may be written in any combination of one or more programming languages, including an object oriented programming language such as Java, Scala, Smalltalk, Eiffel, JADE, Emerald, C++, C#, VB.NET, Python or the like, conventional procedural programming languages, such as the "C" programming language, Visual Basic, Fortran 2003, Perl, Common Business Oriented Language ("COBOL") 2002, PHP: Hypertext Processor ("PHP"), Advanced Business Application Programming ("ABAP"), dynamic programming languages such as Python, Ruby and Groovy, or other programming languages. The program code may execute entirely on the user's computer, partly on the user's computer, as a stand-alone software package, partly on the user's computer and partly on a remote computer or entirely on the remote computer or server. In the latter scenario, the remote computer may be connected to the user's computer through any type of network, including a local area network (LAN) or a wide area network (WAN), or the connection may be made to an external computer (for example, through the Internet using an Internet Service Provider) or in a cloud computing environment or offered as a service such as a Software as a Service (SaaS).

Various embodiments were described herein with reference to flowchart illustrations and/or block diagrams of methods, apparatus (systems), devices and computer program products according to various embodiments described herein. It will be understood that each block of the flowchart illustrations and/or block diagrams, and combinations of blocks in the flowchart illustrations and/or block diagrams, can be implemented by computer program instructions. These computer program instructions may be provided to a processing circuit of a general purpose computer, special purpose computer, or other programmable data processing apparatus to produce a machine, such that the instructions, which execute via the processing circuit of the computer or other programmable instruction execution apparatus, create a mechanism for implementing the functions/acts specified in the flowchart and/or block diagram block or blocks.

These computer program instructions may also be stored in a computer readable medium that when executed can direct a computer, other programmable data processing apparatus, or other devices to function in a particular manner, such that the instructions when stored in the computer readable medium produce an article of manufacture including instructions which when executed, cause a computer to implement the function/act specified in the flowchart and/or block diagram block or blocks. The computer program instructions may also be loaded onto a computer, other programmable instruction execution apparatus, or other devices to cause a series of operations to be performed on the computer, other programmable apparatuses or other devices to produce a computer implemented process such that the instructions which execute on the computer or other programmable apparatus provide processes for implementing the functions/acts specified in the flowchart and/or block diagram block or blocks.

The flowchart and block diagrams in the figures illustrate the architecture, functionality, and operation of possible implementations of systems, methods, and computer program products according to various aspects of the present disclosure. In this regard, each block in the flowchart or block diagrams may represent a module, segment, or portion of code, which includes one or more executable instructions for implementing the specified logical function(s). It should also be noted that, in some alternative implementations, the functions noted in the block may occur out of the order noted in the figures. For example, two blocks shown in succession may, in fact, be executed substantially concurrently, or the blocks may sometimes be executed in the reverse order, depending upon the functionality involved. It will also be noted that each block of the block diagrams and/or flowchart illustration, and combinations of blocks in the block diagrams and/or flowchart illustration, can be implemented by special purpose hardware-based systems that perform the specified functions or acts, or combinations of special purpose hardware and computer instructions.

The terminology used herein is for the purpose of describing particular aspects only and is not intended to be limiting of the disclosure. As used herein, the singular forms "a", "an" and "the" are intended to include the plural forms as well, unless the context clearly indicates otherwise. It will be further understood that the terms "comprises" and/or "comprising," when used in this specification, specify the presence of stated features, steps, operations, elements, and/or components, but do not preclude the presence or addition of one or more other features, steps, operations, elements, components, and/or groups thereof. As used herein, the term "and/or" includes any and all combinations of one or more of the associated listed items and may be designated as "/". Like reference numbers signify like elements throughout the description of the figures.

Many different embodiments have been disclosed herein, in connection with the above description and the drawings. It will be understood that it would be unduly repetitious and obfuscating to literally describe and illustrate every combination and subcombination of these embodiments. Accordingly, all embodiments can be combined in any way and/or combination, and the present specification, including the drawings, shall be construed to constitute a complete written description of all combinations and subcombinations of the embodiments described herein, and of the manner and process of making and using them, and shall support claims to any such combination or subcombination.

The invention claimed is:

1. A system comprising:
an input interface;
a processor circuit; and
a memory comprising machine-readable instructions that, when executed by the processor circuit, cause the processor circuit to:
receive, by the processor circuit and via an operator processor circuit, an identification of a plurality of games stored in an electronic gaming machine (EGM);
receive, by the processor circuit and via the input interface, external data corresponding to an event or condition that is external to the EGM, wherein the external data comprises a history-based prediction of a type of game that a player has played and of an amount of time that the player has played the type of game;
determine a recommended game set of a plurality of game sets using artificial intelligence and based on the external data, wherein determining the recommended game set includes determining, using the history-based prediction, that an undownloaded game of the recommended game set is downloadable by the EGM before a game session ends; and
transmit, to the EGM, an indication comprising a game set switch to the recommended game set, wherein the indication causes the EGM to download the undownloaded game prior to performing the game set switch to display the recommended game set.
2. The system of claim 1, wherein the external data corresponds to the player that is playing the EGM.
3. The system of claim 2, wherein the external data corresponding to the player comprises image data generated by a camera at the EGM.
4. The system of claim 1, wherein the processor circuit is further configured to receive, from the operator processor circuit, a request for the recommended game set, and wherein determining the recommended game set is performed responsive to receiving the request.
5. The system of claim 1, wherein responsive to an active current game set being switched to the recommended game set, the processor circuit is further configured to receive feedback data that corresponds to the recommended game set after the current game set is switched.
6. The system of claim 1, wherein the processor circuit is further configured to receive game set metrics that comprise quantitative data corresponding to performance of ones of the plurality of game sets.
7. The system of claim 1, wherein the processor circuit is further configured to determine an order of games within one of the plurality of game sets, and wherein the order of games defines the order sequence that the games within the one of the plurality of game sets are presented to the player.
8. The system of claim 1, wherein the processor circuit is further configured to cause a message to be sent to the player of the EGM, wherein the message comprises an invitation to change to a second EGM to access one of the plurality of game sets that is not on the EGM.
9. The system of claim 8, wherein the message further comprises an incentive to the player to switch to the second EGM.
10. The system of claim 8, wherein the message further comprises directions to the second EGM from the EGM.
11. The system of claim 1, wherein the processor circuit is further configured to cause a message to be sent to a player that is not in a first venue, wherein the message comprises an invitation to go to the first venue to access one of the plurality of game sets that is not at a player location and directions for the player to go to the first venue.

19

12. The system of claim 11, wherein the processor circuit is caused to:
 receive a confirmation that the player is going to the first venue; and
 cause the one of the plurality of game sets to be switched 5 to access the one of the plurality of game sets while the player is to the first venue.

13. The system of claim 1, wherein the processor circuit is further configured to cause a message to be sent to a player, wherein the message comprises a request from the player to an operator to get one of the plurality of game sets. 10

14. The system of claim 1, wherein the artificial intelligence comprises a first artificial intelligence that is provided by the processor circuit, and wherein the processor circuit is further configured to receive a request from the EGM that comprises a second artificial intelligence that is provided by the EGM. 15

15. The system of claim 14, wherein the second artificial intelligence is configured to determine an EGM specific recommended set based on EGM data that is specific to the EGM. 20

16. The system of claim 15, wherein the EGM data that is specific to the EGM comprises EGM environmental data. 25

17. A host device comprising:

a processor circuit; and
 a memory comprising machine-readable instructions that, when executed by the processor circuit, cause the processor circuit to:
 receive, by the processor circuit and via an operator processing circuit, identification corresponding to a plurality of game sets, each of the plurality of game sets comprising a subset of a plurality of games; 30
 determine a recommended game set switch from a first one of the plurality of game sets to a second one of the plurality of game sets that are on an electronic gaming machine (EGM) using artificial intelligence that uses external data to identify the second one of the plurality of game sets, wherein the external data comprises a 35

20

history-based prediction of a type of game that a player has played and of an amount of time that the player has played the type of game and wherein determining the recommended game set includes determining, using the history-based prediction, that an undownloaded game of the recommended game set is downloadable by the EGM before a game session ends; and
 transmit, to the EGM, an identification of the recommended game set switch, wherein the identification causes the EGM to download the undownloaded game prior to performing the game set switch to display the recommended game set.

18. A method comprising:

receiving, by a processor circuit, an identification of a plurality of games stored in an electronic gaming machine (EGM);
 receiving, by the processor circuit, an identification of a plurality of game sets, each of the plurality of game sets comprising a subset of the plurality of games;
 receiving, by the processor circuit, external data corresponding to a factor that is external to the EGM, wherein the external data comprises a history-based prediction of a type of game that a player has played and of an amount of time that the player has played the type of game;
 determining a recommended game set using artificial intelligence and based on the external data, wherein determining the recommended game set includes determining, using the history-based prediction, that an undownloaded game of the recommended game set is downloadable by the EGM before a game session ends; and
 transmitting, to the EGM, an indication comprising a game set switch to the recommended game set, wherein the indication causes the EGM to download the undownloaded game prior to performing the game set switch to display the recommended game set.
